YARN-REEL.

No. 920,777.

Specification of Letters Patent.

Patented May 4, 1909.

Application filed December 1, 1908. Serial No. 465,549.

To all whom it may concern:

Be it known that I, ALONZO E. RHOADES, a citizen of the United States, and resident of Hopedale, county of Worcester, State of Massachusetts, have invented an Improvement in Yarn-Reels, of which the following description, in connection with the accompanying drawing, is a specification, like numerals on the drawing representing like parts.

10 This invention has for its object the production of a yarn reel having various novel features of construction and arrangement relating more particularly to the mechanism for measuring the length of the yarn wound 15 upon the swift and for effecting automatically the stoppage of the apparatus when a hank of predetermined length has been completed.

Inasmuch as certain features of the apparatus herein shown are old they will be referred to only in such detail as will be sufficient to a proper understanding of such parts in connection with the novel features. Such novel features will be described fully in the 25 joined specification and particularly pointed out in the following claims.

Figure 1 is a front elevation of the driving end of a yarn reel with my present invention embodied therein, one end of the swift being shown and a portion of the traversing guide-bar; Fig. 2 is a transverse section on the irregular section 2-2, Fig. 1, looking toward the left; Fig. 3 is a vertical section through the clock or measuring mechanism; Fig. 4 is an inner side view of the gong and striker, at the left of the line 4-4, Fig. 3; Fig. 5 is an inner side elevation of the scroll which in practice forms a casing for other parts of the measuring mechanism, the differential pinions also being shown; Fig. 6 is a view of the disk which is rotatably mounted in the open end of the scroll, the view showing the disk as it would appear when looking at it from the left, Fig. 3, supposing the scroll and gong to be removed; Fig. 7 is a top plan view, broken out, of a portion of the shipper releasing means.

The main driving shaft 1, having a bearing in the end frame 2, has connected with it the 50 reel or swift comprising the longitudinal bars 3, Fig. 1, connected by arms 4 with the center shaft 5 and is of usual construction in apparatus of this character, the swift being rotated by the main shaft 1. The latter is 55 provided with fast and loose pulleys 6, 7, Figs. 1 and 2, to receive a belt from a suitable

source of power, the belt in practice being shifted from one to the other pulley by a shipper 8 slidably mounted on a fixed guide 9, a lever 10 having a fixed fulcrum on bracket 60 11 being connected at one end with the shipper by a link 12. At its other, upper end said lever is pivotally connected by a stud 13 with a horizontal shipper rod 14 extended the length of the reel frame and slidably sus- 65 tained in bearings 15 on the front board 16, this construction being substantially of well known construction.

The shipper is shown in Fig. 1 in running position, and herein I have provided means 70 to retain it in such position and to move it into stopping position automatically.

Referring to Fig. 7, a controller, shown as a rod 17, is supported in suitable bearings, as 18, adjacent and parallel to the shipper 75 rod and provided with a fixedly attached, forked collar 19 which loosely embraces said shipper rod, the forked portion of the collar being adapted to engage a collar 20 fast on the rod 14.

A strong actuating spring 21 is coiled around the controller 17 between the forked collar and an adjacent one of the bearings 18, the spring tending when free to act to move the controller and the shipper rod to 85 the right, Fig. 7, to thereby swing the lever 10 and through the link 12 shift the shipper 8 to the left, Fig. 1, to shift the belt from the fast to the loose pulley.

The controller has fast upon it near its 90 outer end a coned collar 22 behind the flat face of which rests a latch 23 when the apparatus is running, as shown in Figs. 1, 2 and 7, the latch thus acting to retain the actuating spring 21 compressed and the 95 shipper in running position.

When the latch is withdrawn from co-operation with the collar 22 the controller 17 is released, the spring expands, and through the connection between the controller and 100 the shipper rod 14 the shipper is moved to stopping position.

As shown in Figs. 2 and 7 the upper end of the latch is notched or shouldered at 24 for a purpose to be described, and said latch 105 is pivoted at its lower end at 25 on an extension 26 secured to a strut 27 forming a part of the main frame, the extension having a stop 28 to co-operate with a lug 29 on the lower end of the latch to limit retractive 110 movement thereof.

The novel mechanism for releasing the

latch will be described hereinafter in connection with other parts of the apparatus.

Outside of its bearing on the end frame 2 the main shaft 1 has an attached bevel gear 30 which meshes with and drives a similar gear 31 fast on an upright shaft 32 supported in fixed bearings 33 on the frame, a pinion 34 fast on the upper end of the shaft meshing with a pinion 35 having its shaft sustained 10 in an extension 36 of the upper bearing 33. Said pinion 35 carries a disk 37 having a connected wrist-pin 38 pivotally attached to one end of a link 39, the inner end of the latter being connected at 40, Fig. 1, with the 15 usual traversing guide-bar 41, provided in practice with pig-tails or other guides for the yarns, the guide-bar being reciprocated longitudinally in usual manner by or through rotation of the disk 37, as will be manifest.

20 The traverse motion is actuated from the main shaft 1 through the shaft 32, and in my present invention I have provided means whereby the measuring mechanism is actuated from said shaft, as will be described.

25 A worm 42 on shaft 32 meshes with and drives a worm gear 43 fast on the outer end of a horizontal shaft 44 rotatably mounted in a fixed sleeve bearing 45, a large gear 46 being secured to the inner end of shaft 44 30 and meshing with an intermediate change gear 47 the short shaft of which is carried by a bearing 48 adjustably mounted on an arm 49 extended from the bearing 45. By this arrangement intermediate gears of different diameters can be used between the gear 46 and a small gear or pinion 50 the shaft 51 of which, see Fig. 3, is shouldered to receive the pinion, held fast thereon by a nut 52, the shaft rotating in a fixed bearing 40 53, Figs. 1 and 3.

The outer or left-hand end of the shaft 51 has fixed upon it a disk 54, shown separately in Fig. 6, carrying an eccentric stud 55 on which is rotatably mounted a wide-faced 45 pinion 56, herein shown as provided with sixteen teeth, said pinion having a planetary motion as it is revolved bodily with the disk 54 and also rotates on its own axis 55.

As shown in Fig. 3 the outer end of shaft 50 51 is centrally socketed to receive loosely the reduced end 57 of a stud 58 fixedly mounted in a bracket 59 on the main frame, the stud having attached to it a gong 60 and an arm 61 on which is mounted a rocking, spring 55 controlled hammer or striker 62, of usual construction, the spring normally holding a tail 63 (fast on the hammer shaft) against a stop 64 on the arm 61, see Figs. 3 and 4.

Adjacent the outer end of shaft 51 a pinion 60 65 is fixed on the stud 58 in mesh with the planetary pinion 56, a second pinion 66 also in mesh with pinion 56 being fixedly mounted on the shouldered hub 67 of a cylindrical casing 68 provided on its exterior with a 65 scroll or spiral groove 69, the disk 54 entering

the open inner end of the casing, as shown in Fig. 3, and thereby inclosing the planetary pinion and the differential pinions 65 and 66.

The hub 67 is mounted to rotate on stud 58 between the stationary pinion 65 70 and the hub of the arm 61, so that while the scroll-casing is free to rotate it is held from movement longitudinally of the stud 58. Pinion 65 herein has nineteen teeth, and pinion 66 has eighteen teeth, and as the disk 54 75 is revolved the pinion 56 will be rotated on its own axis by engagement with the stationary pinion 65, but such axial rotation of the pinion 56 will in turn impart rotation to the differential pinion 66 and its attached 80 scroll-casing. The shaft 51 and attached disk 54 rotate in the direction of arrow 70, Fig. 6, and the bodily revolution of pinion 56 with the disk causes the said pinion to rotate on its own axis in the direction of arrow 85 71, due to its engagement with the fixed differential pinion 65, but as the latter has 19 teeth, and the pinion 56 has 16 teeth the latter, meshing with the loose pinion 66 (having 18 teeth) will cause such loose pinion to 90 rotate in the opposite direction, indicated by arrow 72, Fig. 5. As the loose differential pinion 66 is fixedly connected with the scroll casing 68 the latter will be turned in the direction of arrow 72, and at a very slow rate of 95 speed.

In practice each complete turn of the scroll 69 is equivalent to a given number of yards of yarn wound upon the reel or swift, and I have arranged a lug 73 on the face of the casing adjacent the gong 60, to engage the tail 63 of the striker 62 once for each revolution of the scroll casing, to thereby ring the gong in a manner easily understood. Such an audible signal notifies the attendant that the scroll has completed one turn, equal to a given number of yards, and I have provided the end of the scroll with a recess 74 by cutting through the cylindrical wall of the casing 68. The upturned tip of a finger or pawl 75, partly shown in dotted lines Fig. 2 is adapted to enter the scroll groove or spiral from below, the finger being fast on a sleeve 76 mounted to rock and slide on a horizontal guide rod 77 fixedly secured to the bracket 59, the sleeve having a frontwardly extended arm 78 from which depends a pivoted link 79 fast on a lateral hub or sleeve 80. Said sleeve is mounted to rock and slide on a horizontal rod 81 fixed on the front end of an arm 82 110 which is secured to or forms a part of the two-part eccentric strap 83, best shown in Fig. 2, which surrounds an eccentric 84 fast on the main shaft 1, and also for convenience made in two parts. Disks 85 fast on the shaft confine the strap in proper position on the eccentric, and as the shaft rotates the eccentric effects longitudinal movement of the arm 82 back and forth, the arm being held up in the position shown in Fig. 2 as long as the 120 130

finger 75 is in engagement with the scroll. The arm travels in a guide 86 fixed to a bracket 87 on the end frame 2 and is thereby held from lateral movement, said arm having 5 adjustably attached to it by screws 88, Fig. 2, a trip 89, having its end hooked at 90 and adapted to at times engage the shouldered end 24 of the latch 23. The weight of the parts suspended from the sleeve-arm 78 normally 10 acts to retain the finger 75 in engagement with the bottom of the scroll groove, and at the same time the tripping arm 82 and trip 89 thereon will reciprocate above the shouldered end of the latch and the shipper 15 actuator or spring 21 will be held from operation, as shown in Fig. 7.

When the reeling of the yarn has proceeded far enough to bring the recess 74 of the scroll 69 opposite the tip of the finger 75 the latter will be swung inward toward the axis of the scroll, and the sleeve 76 rocks on the guide-rod 77, permitting the trip to drop into position to engage the latch. On the next backward stroke of the trip 89 the latch 23 is swung rearward, releasing the collar 22 and the actuating spring 21 is then free to move the shipper rod 14 to the right, Fig. 7, to thereby shift the belt from the fast pulley 7 to the loose pulley 6, and the machine is stopped. It will be evident that as the scroll rotates the finger 75 must move laterally, and this is provided for by slidably mounting the sleeve 76 and the hub 80 on the fixed guide-rod 77 and 81.

If the full length of yarn which the scroll can measure is to be wound upon the swift the finger 75 will be applied to the scroll at the starting point of the spiral, as will be manifest, but if a shorter length of yarn is to be wound the finger will be started at such a point on the scroll as will effect automatic stoppage of the apparatus when the desired length has been reeled.

An adjustable stop-collar 91 is mounted on 45 the guide-rod 77 at the left of the sleeve 76, so that all the attendant has to do in resetting the finger at the beginning of the reeling is to move the said finger until its sleeve abuts against the stop-collar.

The trip-carrying arm 82 has a constant 50 stroke, and the adjustment of the trip 89 on the arm provides for taking up wear or for getting the trip into proper relation to the latch when the trip-carrier 82 is lowered to operative position.

When the shipper rod 14 is moved to start the apparatus, (in practice by the usual handle not herein shown) the controller rod 17 is moved with it, and the collar 22 is made 55 conical at its outer end, as shown in Fig. 7, in order to slide past the latch 23 and let the latter drop back behind the collar into locking position.

The measuring or "clock" mechanism, 60 as it is frequently termed, is operated from

the traverse-motion actuating shaft 32 through the train of gearing 43, 46, 47, 50 and the proper rotative speed of the scroll is secured through the differential pinions 65, 66 and planetary pinion 56 on the disk 54 70 driven from the small gear or pinion 50 of the above-mentioned train of gearing.

A very accurate measurement of the length of yarn reeled is effected by the apparatus, and the stop-motion is actuated automatically when the desired length of yarn has been reeled upon the swift, it being understood that in practice a large number of hanks will be reeled simultaneously, and all will contain the same number of yards of 75 yarn.

Having fully described my invention, what I claim as new and desire to secure by Letters Patent is:—

1. In a yarn reel, a driving member, an 85 instrumental to throw the power on and off said member, an actuator to operate said instrumental to throw off the power, means to normally maintain the actuator inactive, a device to release said means, 90 measuring mechanism, including a scroll and a coöperating finger, and connections between the finger and the releasing device to cause the latter to release the actuator and permit it to cause the power to be thrown 95 off after a predetermined operation of the reel.

2. In a yarn reel, a driving member, means, including a spring actuator, to throw off the power, a latch to normally maintain 100 said means inoperative, a trip, a carrier therefor reciprocated by the driving member adjacent the latch, measuring mechanism, operating connections between it and the driving member, and means controlled by 105 said mechanism to permit coöperation of the trip and latch to render the latter inoperative when the measuring mechanism indicates a predetermined length of yarn reeled.

3. In a yarn reel, a driving member, 110 means, including a spring actuator, to throw off the power, a latch to normally maintain said means inoperative, a trip, a carrier therefor reciprocated by the driving member adjacent the latch, measuring mechanism, 115 including a laterally movable rocking finger, operating connections between said mechanism and the driving member, and connections between the finger and the trip-carrier to retain the latter and the trip inoperative with 120 respect to the latch until the finger is permitted to rock when a predetermined length of yarn has been reeled.

4. In apparatus of the class described, a 125 swift, a traverse-motion, a rotatable driving member operatively connected with the swift and said traverse-motion, a shipper, a latch to retain it in running position, a spring to move the shipper to stopping position, and normally inoperative latch releasing 130

- means, combined with a rotatable casing provided with a measuring scroll, differential pinions, one rotatable with the casing and the other fixed, a pinion in mesh with the differential pinions, means to revolve said pinion bodily about the differential pinions, to thereby effect rotation of the scroll, a finger to travel in the scroll and adapted to rock when the end of the scroll is reached, and a controlling connection between the finger and latch releasing means, to effect movement of such means to operative position when the finger rocks and permit movement of the shipper to stopping position.
- 15 5. In a yarn reel, a driving member, a traverse-motion actuating shaft driven by said member, a shipper, means to move it to stopping position automatically, a measuring scroll, differential gearing to effect rotation thereof, a train of transmitting gears between said gearing and the actuating shaft of the traverse-motion, a finger coöoperating with the scroll and adapted to rock when the end of the scroll is reached, and a controlling 20 connection between the finger and the shipper moving means to permit such means to move the shipper to stopping position when the finger reaches the end of the scroll.
- 25 6. In apparatus of the class described, a driving member, a shipper, a spring to move it to stopping position, a latch to retain the shipper in running position, and a trip nor-

5 mally reciprocated adjacent the latch by said driving member, combined with a scroll, transmitting and differential gearing between the driving member and the scroll, to rotate the latter, a fixed guide parallel to the axis of the scroll, a finger mounted to rock and slide upon the guide and to coöperate with the scroll, a connection between the finger and the trip to prevent coöperation between the trip and the latch until the finger reaches the end of the scroll and is permitted to rock on the guide, and an adjustable stop on the guide to determine the point at which coöperation of scroll and finger shall begin.

7. In a reel having a swift, a driving member therefor, a stopping instrumentality for the reel, and an audible alarm, combined with measuring mechanism, including a revolute scroll, means to sound the alarm at each revolution of the scroll, and a device to render the stopping instrumentality operative automatically when the measuring mechanism indicates the reeling of a predetermined length of material upon the swift.

In testimony whereof I have signed my name to this specification, in the presence of two subscribing witnesses.
